UNITED STATES PATENT OFFICE.

THOMAS DE LA MARE, OF TOOKEE, UTAH.

CONCRETE MOLD OR FORM.

1,389,128.

Specification of Letters Patent. Patented Aug. 30, 1921.

Application filed April 20, 1920. Serial No. 375,825.

To all whom it may concern:

Be it known that I, THOMAS DE LA MARE, a citizen of the United States, residing at Tooele, in the county of Tooele and State 5 of Utah, have invented a new and useful Concrete Mold or Form, of which the following is a specification.

The present invention appertains to concrete molds or forms, and is particularly an 10 improvement over the conduit mold disclosed in my Patent No. 1,118,558, issued November 24, 1914.

One of the objects of the present invention is the provision of a mold or form of 15 novel construction, which enables different diameters of conduits to be molded, the device including concentric core shells which are detachably connected whereby they may be used in conjunction for molding a conduit of larger diameter, and whereby the 20 inner shell may be withdrawn and used by itself for molding a conduit of smaller diameter.

Another object of the invention is the provision of an appliance adapted for the 25 construction of gutters, channels or sluices having sides of different heights.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, can be made within the scope of what is claimed, without departing from the spirit of the invention.

The invention is illustrated in the accompanying drawing, wherein:—

Figure 1 is a longitudinal section of the mold, portions being broken away.

Fig. 2 is an enlarged end view of the mold in contracted position, and illustrating 45 the same used for forming a gutter having a low side and a high side, portions of the mold being shown in section.

Fig. 3 is a view similar to Fig. 2 illustrating the mold in expanded position, and 50 showing the mold used for forming a channel or gutter having sides of equal height.

Fig. 4 is a sectional detail taken on line 4—4 of Fig. 2.

Fig. 5 is a sectional detail taken on the 55 line 5—5 of Fig. 1.

In carrying out the invention, there is

provided a cylindrical core shell 1 constructed of resilient sheet metal, and divided longitudinally, as at 2, the shell 1 having an expansive tension whereby it will expand 60 when released.

The means for limiting the expansion of the shell 1 and for contracting the same, embodies a pair of hubs 3 in the opposite ends of the shell 1 and connected by toggle links 4 with the shell. A spindle 5 disposed axially within the shell 1 has one end portion threaded through one of the hubs 3, and a stem or rod 6 is threaded through the other hub 3 and its inner end is slidably received 70 by a bore 7 provided in the other end of the spindle 5, whereby the spindle 5 and stem 6 are slidably connected. The outer end of the stem 6 has an angularly projecting portion 8 to which is pivoted one end of the 75 T-head 9 of a lever 10. A rod or link 11 has an angularly extending portion 12 at one end pivoted to the other end of the head 9, and has an angularly extending portion 13 at its other end pivoted to the spindle 5 80 near the remote end thereof, the rod 11 extending longitudinally within the shell 2.

When the lever 10 is swung at approximately right angles with the stem 6, as seen in Fig. 1, the head 9 will act to push the stem 6 inwardly and to pull the rod 11 in the opposite direction, so that the hubs 3 are moved toward one another to straighten out the toggle links 4, whereby the shell 1 is expanded. When the lever 10 is swung 90 to this position, it will be swung into or beyond its dead center, so that the lever 10 will hold its position until released. When the lever 10 is swung backwardly, the rod 11 is pushed ahead by the lever 10 and the 95 stem 6 is pulled outwardly, whereby the hubs 3 are separated, thus causing the links 4 to pull the walls of the shell 1 inwardly, thereby contracting the shell.

When the shell 1 is of considerable length, additional means for controlling the expansion and contraction of the shell are employed. Thus, hubs 14 between the hubs 3 are disposed slidably upon the spindle 5 to be guided thereby, and are connected by 105 toggle links 15 with the shell 1, the same as the hubs 3 are. The hubs 14 are connected with the respective end hubs 3 by means of links 16, so that the hubs 14 will be moved toward and away from one another the 110 same as the hubs 3. This causes the links 15 to act the same as the links 4, and the shell

will therefore be contracted and expanded the same throughout its length.

The shell 1 may be used in the formation of concrete conduits and the like, as disclosed in the said patent supra, and further description along this line is not deemed necessary, since reference may be had to the said patent.

The invention also includes a second and 10 larger cylindrical core shell 17 divided longitudinally, as at 18, and constructed of resilient sheet metal. The shell 17 is of larger diameter than the shell 1 so as to surround or envelop the same concentrically. This 15 shell 17 may be disposed over and attached to the shell 1 when it is desired to mold a conduit of larger diameter, the same as a smaller conduit is molded by the shell 1. One end of the shell 1 is detachably connected to the respective end of the shell 17 20 by a plurality of radial stays 19 having angularly bent ends 20 lying against the shells and detachably secured thereto by means of bolts or other removable securing 25 elements 21. The other ends of the shells are connected by a plurality of radial stays 22 having angularly extending ends 23 detachably secured to the outer shell 17 by means of removable bolts or other securing 30 elements 24. The inner ends of the stays 22 have angularly extending hooks 25 receiving the respective end of the shell 1, to provide a slip joint between the stays 22 and shell 1. In assembling the two shells, the 35 shell 1 is moved longitudinally within the shell 17 so as to slide between the stays 19, and the respective end of the shell 1 is then slipped into the hooks 25 so as to be held in place by the stays 22. The shell 1 is 40 then bolted or fastened to the stays 19, which will hold the shell 1 in place within the shell 17. Then, when the shell 1 is contracted, the shell 17 will be contracted there- 45 with due to the fact that the stays 19 and 22 connect the two shells. When the shell 1 is allowed to expand, the shell 17 will also expand, which enables the shell 17 to be used for molding a conduit of larger diameter the same as a conduit of smaller diameter is formed by the shell 1. The space 50 between the edges of the shell 17 may be closed by a curved plate 26, if desired, and this plate 26 may also be used for closing the space between the edges of the shell 1.

55 The shell 17 is adapted for forming a gutter, channel or sluice having straight up- 60 standing sides, and to this end a pair of angle iron members 27 are attached to the sides of the shell 17. The members 27 have upper inwardly projecting and outer downwardly projecting sides whose edges seat against the sides of the shell 17, and said flanges are provided with suitable apertures 28 to coöperate with corresponding apertures 28^a provided in the sides of the shell

17, in order that bolts or other securing elements 29 may be engaged through suitable apertures 28 and 28^a for fastening the members 27 to the shell 17 at the proper position.

The shell 17 may now be employed for 70 forming a concrete gutter, channel or sluice G, as indicated in Fig. 3, and the members 27 will facilitate the formation of the straight upstanding sides S of the gutter. It will be noted that the members 27 have 75 vertical flanges tangential with the shell 17 whereby the sides S of the gutter may be properly formed, and the sides S may be formed to equal heights, by bringing their edges flush with the upper flanges of the 80 members 27.

Members 27 of different sizes may be used, and members 27 of smaller sizes may be used in connection with the shell 1, the same as with the shell 17, for obvious reasons. The members 27 may also be adjusted relative to the shell owing to the provision of the arrangement of the apertures 28 and 28^a.

When it is desired to mold a gutter having a low side and a high side, an upstanding plate 30 is attached to the upright flange of one of the members 27, the plate 30 having apertures 31 through which bolts 33 may be engaged to engage through certain apertures 28 of the respective member 27 for fastening the plate 30 in place. The gutter G' may therefore be molded with a low side S', and with a high side S'', since the plate 30 forms an extension of the respective member 27 permitting the respective side of the gutter to be formed higher than the opposite side. This is especially valuable for providing a curbing along one side of the gutter.

The members or attachments 27 are removed from the shell 17 when said shell is employed for molding a conduit or the like.

Having thus described the invention, what is claimed as new is:—

1. In a mold, a resilient contractible shell, a second resilient contractible shell encircling the first mentioned shell and means for expanding and contracting the said shells uniformly throughout their circumference.

2. In a mold, a contractible shell, means for contracting and expanding said shell throughout its circumference, a second contractible shell entirely surrounding the first mentioned shell and stays detachably connecting the shells whereby the second shell is contracted and expanded uniformly throughout its circumference in conformity with the expansion and contraction of the first mentioned shell.

3. In a mold, a contractible shell, means for operating said shell, a second contractible shell surrounding the first mentioned shell, stays attached to the second shell adjacent the ends thereof, the stays at one end having portions for receiving the respective end of the first mentioned shell, and

means for detachably securing the other end of the first mentioned shell to the other stays.

4. A mold comprising an inner cylindrical contractible shell divided longitudinally, an outer cylindrical contractible shell divided longitudinally and surrounding the inner shell, means within the inner shell for contracting it, stays having their outer ends attached to the outer shell adjacent the ends thereof, the stays at one end having hooks at their inner ends for receiving the respective end of the inner shell, and means for detachably securing the inner ends of the other stays to the other end of the inner shell.

5. In a mold, a contractible shell, a pair of end hubs therein, hubs between said hubs, toggle links connecting all of said hubs and the shell, a spindle attached to one of the ends hubs, the second mentioned hubs being slideable upon the spindle, a stem engaged with the other end hub and having a sliding connection with the spindle, a lever pivoted to the stem, and a link connecting said lever and the spindle.

6. In a mold, a cylindrical shell, angle members having their flanges resting against

opposite sides of the shell, means for detachably securing said members to the shell, and a plate attachable to one side of one of said members, the plate and said member being provided with means whereby adjustment between the two elements is effected.

7. In a mold, a cylindrical shell, angle members on opposite sides of the shell, said members having their sides resting against the shell, means for detachably securing said members to the shell, and a plate attachable to one side of one of said members to form an extension thereof.

8. In a mold, a cylindrical shell, an angle member having its sides resting against the shell with one side arranged tangentially relative to the shell, means for detachably securing said member to the shell, and a plate detachably secured to said side to form an extension thereof.

In testimony that I claim the foregoing as my own, I have hereto affixed my signature in the presence of two witnesses.

THOMAS DE LA MARE.
